CLAIM

The ornamental design for a warming therapy device, as shown and described.

DESCRIPTION

FIG. 1 shows a perspective view of the invention;

FIG. 2 shows a front view of the invention;

FIG. 3 shows a rear view of the invention;

FIG. 4 shows a right side view of the invention;

FIG. 5 shows a left side view of the invention;

FIG. 6 shows a top view of the invention; and,

FIG. 7 shows a bottom view of the invention.

The broken lines in the FIGS. 1-7 are included for the purpose of illustrating portions of the warming therapy device that form no part of the claimed design.
